UNITED STATES PATENT OFFICE.

ELBERT H. CARROLL, OF WEST BOYLSTON, MASSACHUSETTS, ASSIGNOR TO MORGAN CONSTRUCTION COMPANY, OF WORCESTER, MASSACHUSETTS, A CORPORATION OF MASSACHUSETTS.

COIL-HANDLING APPARATUS.

Application filed December 17, 1923. Serial No. 681,169.

The present invention relates to apparatus for handling coiled material, and in particular involves the provision of mechanism for automatically removing successively formed 5 coils of finished material, such as rods or the like, from the coil forming devices of a metal rolling mill, and for transferring such coils to the coil conveying devices of said mill. The invention resides in the combination and arrangement of parts herein- 10 after set forth in detail, reference being had to the accompanying drawings, wherein—

Fig. 1 is a top plan view of the apparatus embodying the invention.

Fig. 2 is a view in side elevation of the apparatus shown in Fig. 1.

Fig. 3 is a transverse sectional view, on an enlarged scale, of such apparatus, the section being taken on the line 3—3 of Fig. 2.

Fig. 4 is a fragmentary plan view, on an enlarged scale, of a part of the apparatus adjacent the coiling device.

Fig. 5 is a sectional view on the line 5—5 of Fig. 4, and

Figs. 6 to 10 inclusive are diagrammatic views, showing the essential elements of the transferring mechanism in different positions of operation.

Like reference characters refer to like 30 parts in the several figures.

The coil removing and transferring mechanism of the present invention is here shown as interposed between a coil forming and supporting device 1 and a muffle or other 35 suitable conveyor 2, the latter adapted for the flatwise passage of the coils there- through, with said coils supported on the floor 3 of said conveyor, and moved along said floor in any suitable manner, as by lugs 4, 4, on an endless conveyor chain 5, which lugs project upwardly through a slot in the floor 3 to engage the inner peripheries of successive coils. By any suitable means, well-known in the art, each hot finished piece 40 emerging from the mill is formed into a coil around the upstanding guide fingers 6, 6 of the device 1, being supported during this operation on an apertured plate 7 through which said fingers project; while the coil is being formed the plate 7 occupies the lower dotted line position shown in Fig. 2, and after completion of the coil, said plate is elevated in the usual manner to support the formed coil 8 above the fingers 6, 6, thus to

facilitate its transfer to the conveying de- 55 vice 2, as hereinafter described.

The said conveying device 2 provides a trough-like extension 9, the floor 10 of which is substantially flush with the floor 3; at its end adjacent to the coil supporting device 1, said floor 10 has pivoted thereto the wings 11, 11', whose outer edges conform substantially to the circular edge of the plate 7. In this way, a substantially continuous plane surface is always insured for the flatwise 60 movement of successive coils from the plate 7 to the floor of trough 9, since the wings 11, being hinged, will invariably adjust themselves to variations in the height to which said plate is elevated. The floor 10 of trough 9 is longitudinally slotted as at 12, for the passage of lugs 13 on a suitable endless chain 14. As shown in the drawings, the latter drives a sprocket wheel 15 on a driving shaft 16 of the mechanism, and passes 65 around a double sprocket wheel 17, the latter being driven by the endless chain 5 of conveyor mechanism 2, which, in turn, may be driven by any suitable means, not shown.

For sliding each coil as formed, off the 70 plate 7 and across the wings 11 onto the bottom 10 of trough 9, so that it will be in a position to be engaged internally by one of the lugs 13, the invention provides a 75 mechanical hook, operated in synchronism with the lugs 13, and adapted to enter the opening of the coil from the top, so as not to interfere with the operation of the plate 7. This hook, designated 18, is supported at the juncture of two converging bars 19, 19 having parallel extensions 20, 20. The bars 19, 19 are pivoted at 21, 21 to the free ends 80 of parallel lever arms 22, 22, the latter being joined for movement in unison by a cross rod 23 and being themselves pivoted 85 on the opposite sides of the trough 9 at the aligned pivotal points 24, 24.

Motion is imparted to the lever arms 22, 22 to rock them back and forth on their pivots 24, 24 by means of a pair of links 100 25, 25 that connect said lever arms with crank arms 26, 26 of a rotary shaft 27, the latter being driven by suitable gearing 28, 29 and 30 from the shaft 16 of sprocket wheel 15. The crank arms 26 are shorter 105 than the distance separating the pivots 24 from the points of connection of the links 25, and hence the crank arms 22 are caused

to oscillate, rather than to rotate, at each revolution of the shaft 27; this oscillation has an amplitude, at the free ends of arms 22, where the bars 19, 19 are carried, of sufficient extent to accomplish the necessary horizontal traverse of the hook 18, that is, from a point within the circumference of a formed coil on plate 7 to a point where said inner circumference will overlap the slot 12 of trough 9.

10 The necessary vertical movements of the hook 18 to procure its engagement with and disengagement from a formed coil, are permitted by the pivotal connections 21, 21; for effecting these up and down movements, the free ends of the extensions 20, 20 have link connections 31, 31 with the corresponding links 25, 25, and it is to be noted that the pin and slot connections 32, 32 are provided between the links 31 and the extensions 20 to allow of a certain amount of lost motion.

When the mechanism is at rest, while a coil is being formed on the plate 7, the position of the parts is substantially as shown in Figs. 2 and 6, the hook 18 being held above and at one side of the coil supporting means so as not to interfere with the operation of the coil forming mechanism. 25 Upon completion of the coil and simultaneously with the elevation of plate 7, a clutch, not shown, is engaged, so as to rotate the shaft 27 and crank arm 26 through a single revolution, and to advance the chain 14 an appropriate amount.

In the first part of this revolution of crank arm 26, the lever arms 22 are thrown to the left, as shown in Fig. 7, to dispose the hook 18 directly above the completed coil, but this action has very little effect on the height of the hook, since the relative angular position of the pivotal point 33 on link 25 only undergoes a slight change. However, as the crank arm passes through its horizontal position and approaches vertical, as illustrated in Figs. 8 and 9, the pivotal point 33 rises sharply, and projects the hook 18 downwardly into the opening of the coil; as illustrated in Fig. 9, this low position of the hook is maintained, while at the same time it begins to travel to the right, to draw the coil off of plate 7, owing to the reversal of direction which the arms 22 undergo. The pin and slot connection 32 prevents the hook from being lifted away from the coil by the link 31 as the latter is carried into its uppermost position coincident with the passage of the crank arm 26 through the vertical plane, as indicated in Fig. 9, and the withdrawal movement of the coil in this fashion finds the hook at the limit of its right hand movement just as one of the lugs 13 on chain 14 begins to project through the slot 12. Thereafter, the right hand movement of the coil is continued by en-

gagement of said lug with the inner periphery of said coil, and the hook 18 at this point begins to rise, so as to clear the other side of the coil, as illustrated in Fig. 10. Upon the completion of the full revolution 70 of shaft 27, the hook moves from the position shown in Fig. 10 to the position shown in Fig. 6, and is thus in readiness for a repetition of the above described cycle of operations; as soon as another coil has been laid 75 on the plate 7.

It will be understood, of course, that the chain 14 transfers each coil to the conveying mechanism 2 in position to be acted upon by the lugs 4 of the chain 5. My invention, 80 however, is not dependent upon the use of two conveyor chains for moving the coils, since obviously, the chain 5 could be extended around the sprocket wheel 15 and operated, the same as chain 14, in timed relation to the hook 18.

I claim:

1. The combination with a coil forming mechanism, and an endless chain coil conveyor, of a hook normally spaced from said coil forming mechanism, means for operating said hook in synchronism with said endless chain conveyor at the will of an operator, and means guiding said hook to impale a coil and transfer it to said conveyor.

2. The combination with coil forming means comprising a plurality of guide fingers and a plate through which said fingers project, whereby raising of said plate frees a formed coil from said fingers, of a coil conveyor comprising a conveyor chain and a floor, and interposed means adapted for projection from above into the opening of each formed coil for moving it sideways onto the floor of said conveyor.

3. The combination with coil forming means comprising a plurality of guide fingers and a plate through which said fingers project, whereby raising of said plate frees a formed coil from said fingers, of a coil conveyor comprising a conveyor chain and a floor, and a mechanical device for transferring a formed coil sideways to the floor of said coil conveyor, said device engaging 115 said coil by a downward movement into the opening thereof.

4. In apparatus of the class described, a mechanical device for transferring coils from a coil forming to a coil conveying mechanism, means for projecting said device downwardly to impale a coil while supported on said forming mechanism, means for thereafter moving said device in the plane of support of said coil to transfer it to 120 said conveying mechanism, and means for then releasing said coil by upward movement of said device.

5. In apparatus of the class described, a mechanical device for transferring coils 130

- from a coil forming to a coil conveying mechanism, said device having a path of movement in the plane of support of each coil, as the coil is transferred, and above 5 said plane of support as it moves to engage a new coil, whereby each coil is automatically released by the change of the path of movement.
6. In apparatus of the class described, a 10 mechanical device for transferring coils from a coil forming to a coil conveying mechanism, said device being adapted to impale the formed coils, and means to give said device a substantially elliptical path of 15 movement, with one side of said path flattened, corresponding to the plane of movement of the coils, whereby said device will operate on different size coils without adjustment.
- 20 7. In apparatus of the class described, a coil-supporting plate adapted for elevation to free the coil from the projections around which it is formed, in combination with a conveyor onto the floor of which the coil is 25 delivered from said plate, said floor having a pivoted extension whose free end engages the edge of said plate to provide support for the flatwise movement of said coil.
8. In apparatus of the class described, a coil-supporting plate adapted for elevation to free the coil from the projections around which it is formed, in combination with a conveyor onto the floor of which the coil is 30 delivered from said plate, said floor being spaced from said plate, and the space being bridged by flexibly mounted members, conforming to the edge of said plate, and adapted to adjust themselves to the elevation of said plate.
- 35 9. The combination with coil forming means comprising a plurality of guide fin- 40 gers and a plate through which said fingers project, whereby raising of said plate frees a formed coil from said fingers, of a coil conveyor comprising a conveyor chain and a floor, a hook normally disposed above said coil forming means, and means adapted to be set in operation by the operator for moving said hook downwardly to engage the inside of a formed coil, and to withdraw 45 said coil sideways to the floor of said conveyor, said hook then returning to and stopping at its initial position.
10. In apparatus of the class described, a 50 crank, a hook, and four arms or links to convert the rotary motion of said crank into elliptical motion of said hook, whereby to actuate said hook to impale a coil and transfer it sideways from coil forming mechanism to coil conveying mechanism.
- 55 11. In apparatus of the class described, a crank, a hook, and parallel linkage mechanism to convert the rotary motion of said crank into elliptical motion of said hook, whereby to actuate said hook to impale a 60 coil and transfer it sideways from coil forming mechanism to coil conveying mechanism.
12. In apparatus of the class described, a 65 crank, a hook, four arms or links to convert the rotary motion of said crank into elliptical motion of said hook, and a slot and pin connection between two of said arms or links, whereby to actuate said hook to impale a coil and transfer it sideways from 70 coil forming mechanism to coil conveying mechanism, the elliptical path of said hook being flattened on one side by the action of said pin and slot connection, whereby the coil is moved in a horizontal path.

Dated this 13th day of December, 1923.

ELBERT H. CARROLL.
